UNITED STATES PATENT OFFICE.

CHARLES A. TOWNE, OF DRUMRIGHT, OKLAHOMA.

DRILLING BIT.

Application filed June 11, 1924. Serial No. 719,375.

My invention relates to an improvement in drilling-bits.

The typical form of bit now in use comprises a smoothly constructed straightfluted 5 blade, but this is ineffectual in mixing the mud, because of its failure to agitate and stir the mud on account of its very smoothness.

The chief function of my present invention 10 is to overcome this objection, and it consists in a bit having laterally-extending projections which will keep the mud and material thoroughly mixed and agitated, enabling the bailers to remove all the mud, since it is 15 thoroughly mixed and is not allowed to settle in the bottom of the hole.

Frequently it happens that the threaded 20 pin on the bit will break off, or become unscrewed from the drill stem. In the usual style of bits, the blade is so heavy that it 25 cannot be made of any great length, and it falls sidewise in the hole, and especially is it true in the fifteen inch and larger holes. In the event of such an accident occurring, 30 it is frequently impossible to fish the bit out of the hole.

Another object of my present invention is 35 to obviate this difficulty, and it comprises a bit of much greater length for the same weight, and the lugs or projections on the side keeping the bit in an upright position in the hole, thus making it comparatively easy to obtain a hold on the top of the bit with tools made for the purpose, whereby to 40 remove the broken bit from the hole.

In the accompanying drawings:

Figs. 1 and 2 are views of one form of the 45 bit in side elevation and at right-angles to each other;

Fig. 3 is a bottom plan view;

Figs. 4 and 5 are views of slightly modified forms of the bit.

Referring to Figs. 1, 2 and 3, A represents 50 the stem of the bit; and 1 is the cutting end, it preferably having recesses 2 on opposite sides spread and beveled or sharpened at the cutting edge. At the opposite end, it has the usual pin 3, which is threaded to screw to the tool next above.

At intervals and alternately extending at 55 right-angles to each other are the lugs or projections 4, of which there are four shown in the construction illustrated in Figs. 1 and

2. In Fig. 4 there are three lugs or projections 4', two of which extend parallel, and 55 the third or uppermost one at right-angles thereto.

In Fig. 5, there are two of these lugs or projections 4 and these extend at right-angles to each other. This simply illustrates 60 the fact that the number of lugs or projections and their arrangement about the stem or shank may vary according to the requirements.

In this manner I have provided a bit 65 which stirs and agitates the mud, and which is centered, so to speak, in the hole formed.

Other changes might be made in the form and arrangement described without departure from the invention. 70

I claim:

1. A cable tool drill bit having a cutting end, a shank integral with said cutting end and extending upwardly therefrom, a pair of lugs extending laterally in opposite directions from said shank and integral therewith, and a second pair of integral lugs extending laterally in opposite directions from said shank and in a different horizontal plane from the first pair and extending 75 at an angle to said first pair of lugs for holding the shank in spaced apart relation from the walls of the drilled opening, each pair of said lugs being arranged in longitudinal alignment with each other, and the length 80 thereof being substantially coextensive with the length of the cutting end.

2. A cable tool drill bit having a cutting end, a shank integral with said cutting end and extending upwardly therefrom, and a 85 plurality of pairs of lugs arranged in different horizontal planes on the shank, each pair of said lugs extending at an angle to another pair, each of said pairs of lugs extending laterally in opposite directions from 90 said shank and integral therewith, and arranged in horizontal alignment in a horizontal plane for holding the shank in spaced apart relation from the walls of the drilled opening, the width of said lugs being substantially coextensive with the width of the shank, and the length of each pair of lugs 95 being substantially coextensive with the length of the cutting end. 100

In testimony whereof I affix my signature.

CHARLES A. TOWNE.
